(57) **CLAIM**

The ornamental design for a portable electronic device carrier, as shown.

DESCRIPTION

FIG. 1 is a front elevational view of a portable electronic device carrier showing my new design;

FIG. 2 is a rear elevational view thereof;

FIG. 3 is a front top view thereof;

FIG. 4 is a back top view thereof;

FIG. 5 is a right side view thereof; and,

FIG. 6 is a bottom end view thereof.

The electronic device is shown in dashed lines for illustrative purposes only and forms no part of the claimed design.
